LUBRICATING SYSTEM FOR DEEP WELL TOOLS

1,838,045

UNITED STATES PATENT OFFICE

FRANK L. O. WADSWORTH, OF PITTSBURGH, PENNSYLVANIA

LUBRICATING SYSTEM FOR DEEP WELL TOOLS

Application filed August 15, 1922. Serial No. 582,046.

My invention relates generically to a method and apparatus for lubricating the bearings, or wearing surfaces, of various tools which are designed and intended to operate in deep excavations, or at inaccessible points, below the location of the driving motor for such tools; and the general object and purpose of these improvements is to provide a simple and efficient mode of automatically 10 forcing the oil, or other unguent, into all parts of the said bearings, at a predetermined and controllable rate, when the tools are in operation.

Another object of the present invention is 15 to provide a lubricating system which is in no way dependent, in its action, on either the nature or the physical state of the medium surrounding the apparatus for which it is provided; and which is capable of operating 20 equally well in air, steam, or other gas, or in water or other liquid, at any pressure or depth of immersion.

A further purpose of my improvements is 25 to utilize the force of gravity alone in effecting the forced flow of lubricating material to the desired points; and to govern or regulate the application of that force, and thereby vary the rate of that flow, by the action of an independent extraneous force which 30 is subject to control at an accessible point.

Still another object of my invention is 35 the production of a strong, rugged, simple and reliable feed mechanism which is capable of exerting any desired degree of pressure on the mass of lubricant in the supply reservoir and of forcing the most viscous "solid" unguent into the most restricted bearing spaces; thereby effectually precluding the admission thereto of any mud or grit 40 or other deleterious substances.

A further object of my improvements is 45 to provide means for easily restoring the operating parts of the feeding mechanism to their initial position, and for readily replenishing or fully recharging the lubricant reservoir after the latter has been partially emptied, or completely exhausted by the long continued operation of the tool.

In the illustrative embodiments herein- 50 after described my improvements are par-

ticularly directed to the provision of a lubricating system, of the above specified character, for the cutter bearings of deep well boring tools; and a more specific object of the invention, as thus utilized, is to provide 55 for the automatic arrest of the flow of lubricant to such bearings when the boring operations are stopped, or when the drill is being lowered into, or lifted from, the bore hole.

An additional purpose of my improve- 60 ments—when applied to boring tool constructions—is to provide means whereby the weight of the drill stem parts will be utilized to perform the joint functions of effecting the forced flow of the lubricant into the cutter bearings, and of also keeping the cutters in proper pressure engagement with the bottom of the bore hole when the tool is in use.

Other specific features and other special 65 advantages of the present invention will 70 be made apparent, to those skilled in the art, by the more detailed consideration of the various exemplary constructions last mentioned, which are depicted in the accompanying drawings as follows:

Fig. 1 is a central longitudinal section, on the plane 1—1, of one form of my improved lubricating device, as applied to any standard form of rotary drilling tool; Fig. 2 is a cross section on the plane 2—2 of Fig. 1; Fig. 3 is 75 a side elevation, partly in section on the plane 3—3 of Figs. 1 and 2; Fig. 4 is a view, similar to that of Fig. 1, of another boring tool structure embodying my improvements; Fig. 5 is 80 a cross section on the plane 5—5—5 of Fig. 4; Fig. 6 is another central longitudinal section 85 through a third form of my improved rotary drill construction; Fig. 7 is a horizontal cross-section on the plane 7—7 of Fig. 6; Fig. 8 is a gear diagram showing the arrangement of certain parts of the control mechanism of this construction; Fig. 9 is a partial section on the same plane as that of Fig. 6 and illustrates a modification of the feed releasing elements shown in that figure; Fig. 10 is a sectional elevation of a fourth embodiment of my invention, the lower part of this 90 sectional view being taken on the bent plane 10—10—10 of Fig. 11; Fig. 11 is a side elevation of the drill head and cutter elements 95 100

of the last named structure; Fig. 12 is a fragmentary view showing a modification of the feed control mechanism illustrated in Fig. 10; Fig. 13 is an enlarged partial cross section on the plane 13—13 of Fig. 12; Fig. 14 is another central longitudinal section of a fifth exemplification of this invention; Fig. 15 is a partial cross section on the plane 15—15 of Fig. 14; and Fig. 16 is an additional view illustrating still another way of utilizing certain features of my improvements.

In the following explanation of the above enumerated drawings like letters of reference are used, as far as possible, to designate corresponding or equivalent parts of the several exemplary organizations.

The construction shown in Figs. 1 and 2 comprises a drill head 4, which is of the usual form, and which may be provided with any desired type of rotary cutting members; a driving sleeve 6 which screws into the upper and of the said head; and a plunger member 8 which is adapted to slide longitudinally in the sleeve 6 and which is closed at its upper end, by a cap 9 that is screwed onto the lower extremity of the hollow drill stem 11. The head 4 is drilled and threaded to receive and carry a central tube 12 which supports a piston 14 that slides longitudinally in the plunger member 8; and the lower end of this member is closed by a head 16 that slides on the tube 12. It will be seen that the plunger 8 and the driving sleeve 6 form complementary sleeves which are compressed by the force of the weight of the drill and that this force of compression is limited by a suction force created between the plunger 8 and the piston 14. The upper end of this tube is provided with an extension 17 that is surrounded by an annular bushing 18 whose external diameter is substantially the same as that of the tube 12 and which slides tightly in a central bearing 19 on the cap 9. The plunger 8 is provided with three longitudinal keyways 20—20—20 that extend from its upper end to a point somewhat above the head 16; and it is held in nonrotatable relation to the driving sleeve 6 by means of keys 21—21—21 whose heads are engaged by suitable notches 50 at the upper end of the said sleeve, and are locked therein by the clamp ring 22.

The annular space between the sleeve 6 and the tube 12—which is closed at one end by the drill head 4 and at the other by the plunger head 16—constitutes a lubricant reservoir which is in communication with the cutter bearings through a suitable duct or ducts 23. The reservoir can be filled through an opening 24 that is closed by a screw plug 25; and the duct 23 is preferably provided with a needle valve screw 26 which is covered, and locked in place, (after adjustment) by the fibre washer 27 and the plug 25. The recessed end of this plug is also preferably covered

by a fusible metal seal 8, or some other suitable protecting means.

When the drill is in operation the head 4 is supported by the engagement of the cutter elements with the bottom of the bore hole, and the weight of the drill stem and its attached parts is transmitted, through the plunger member 8 and the head 16, to the mass of lubricant in the reservoir, and serves to force it through the valve controlled duct 23, to the bearings of the cutters. When the bore hole is relatively shallow the weight of the drill stem parts is not large and the flow of lubricant can then be properly regulated by the needle valve 26 alone; but as the depth increases this weight becomes so great that it would be impossible to sufficiently restrict the feed of even the most viscous unguents by merely throttling the passage way 23. Under these conditions the feed of the material to the cutter bearings is governed by reducing and controlling the effective pressure on the head 16; and in the construction now under consideration this is effected in the following manner: The piston 14, which is supported on the drill head 4, is provided with a small port 28 that is closed by a downwardly opening ball valve 29; and the bushing 18 is provided with an eccentric edge flange 30 which can be rotatively adjusted so as to vary the size of this port. The annular chamber between the sleeve 8, the bushing 18, the cap 9 and the piston 14 is filled with glycerine or some other suitable liquid which will flow slowly through the restricted opening 28 to the space between the piston 14 and the head 16. The downward movement of the plunger member 8—relatively to the driving sleeve 6—and the resultant discharge of the lubricant from the reservoir below the head 16, is thus regulated and governed by the restricted flow of liquid through the control port 28 and the spring closed valve 29. The resistance to the flow of viscous material, both through the last mentioned openings and also through the throttled duct 23, permits a part of the load pressure on the drill stem to be transmitted to the drill head parts 4 and 14, and correspondingly increases the pressure on the cutter bits. The total load pressure on the plunger member 8—which is thus utilized in part to feed the lubricant and in part to hold the cutter bits in proper engagement with the bottom of the bore hole—can be, in turn, regulated from the surface by tightening up or slackening off the suspension cable that supports the thrust bearing at the upper end of the revolving drill stem.

As the operation proceeds the plunger parts gradually move downward with respect to the drill head parts and the liquid above the piston 14 is gradually transferred to the chamber below that piston—as shown in the partial section view of Fig. 3. When the operation is interrupted and the tool is

raised out of contact with the bottom of the hole, the weight of the suspended drill head parts, 4—6—12—14—18 etc., is carried on the mass of liquid which fills the space between the heads 14 and 16; and the closure of the spring pressed ball valves 29 prevents any reverse movement of separation of the longitudinally reciprocable members. But when the tool has been lifted out of the hole, and the drill stem 11 removed therefrom, the bushing 18 and the flange head 30 can be turned on the extension support 17 so as to completely uncover a large port 31 in the piston 14—thus permitting the liquid to pass freely from the space below to the space above the said piston, and allowing the parts 6 and 8 to be drawn apart to the original position shown in Fig. 1. The seal over the plug 25 can then be melted out or broken, the plug 25 removed, and the lubricant reservoir refilled ready for the next turn in the drilling operations. As the depth increases the ports 23 and 28 are, one or both, reduced in size by a predetermined adjustment or setting of the control elements 26 and 30; and after these adjustments are made the movable elements are locked in place, the one by the plug 25 and the other by the nut 32.

In order to ensure proper working engagement of the mutually reciprocable parts the sliding surfaces of the members 6—8—14, 12—16 and 18—19, are preferably provided with suitable oil retaining grooves and adjustable packing glands—such as are illustrated in Figs. 1 and 3—and these glands are all so arranged as to be readily accessible by a removal of either the drill head 4 or the drill stem cap 9. The plunger parts can also be readily disconnected from the driving sleeve by removing the clamp ring 22 and the keys 21 and then unscrewing the tubular standard 12 from the head 4. In practice this central tube, and its extension 17, is used to carry the flushing liquid—when such liquid is used—from the interior of the hollow drill stem 11 to the passage way 33 which leads to the lower end of the drill head.

In the construction shown in Figs. 4 and 5 there is a tubular driving sleeve 6^a which is screwed onto the end of the drill head 4, and is provided with three longitudinal grooves or keyways 20^a—20^a etc. that extend from the said head to a point somewhat below the upper extremity of the sleeve. A hollow plunger member 8^a is secured directly to the lower end of the drill stem 11, and is attached at its bottom to an elongated spool shaped piston head 16^a which carries an L shaped ring 16^{aa} that is provided on its periphery with three projecting lugs or keys 21^a for engaging the keyways 20^a. A central tube 12^a is rotatably secured, at its lower extremity, to the head 4, by means of the tapered collar 35 and the threaded sleeve 36; and is slidably engaged, at its upper end, by

the bearing 19^a in the top of the tubular bushing 9^a which couples the central stem of the piston 16^a to the upper head of the plunger 8^a. The lower portion of this central tube is threaded to receive a nut 37 that is loosely confined in a closed pocket between the bottom of the piston head 16^a and the inwardly turned flange of the L shaped ring 16^{aa}; and a ring of balls 38 is inserted between the adjacent faces of the said nut and piston head. The nut 37 is provided with an internal gear collar 39, and the teeth of this gear are engaged by a pinion 40 on the vertical shaft 41. The opposite end of this shaft carries another pinion 42 which is in mesh with the spur gear 43 that is revolvably mounted on the lower end of the bushing 9^a. The gear 43 is coupled, by a pawl and ratchet connection, to the clock spring drum 44 which is also revolvably mounted on the bushing 9^a and is provided, at its upper end, with an internal winding gear 45 that is engaged by the key pinion 46. The drum 44 carries a powerful spiral spring 47 which is attached at its outer end to the tubular extension 48 of the piston 16^a. The uncoiling of this spiral spring revolves the drum 44 and the pawl connected gear 43, and this, in turn, rotates the nut 37 (through the pinion and gear connections, 42—41—40—39) in such direction as to move it downwardly on the stationary screw threaded tube 12^a. In order to control and govern the speed of this movement the shaft 41 is connected, through the train of gearing 100 50—51—52—53—54—55—56—57 to an ordinary balance or escapement wheel 58.

The space below the piston members 16^a—16^{aa} is filled with lubricant through the opening 24 and the latter is then hermetically closed by the plug 25 and a suitable seal, s. The spring 47 is wound up on the drum 44 by means of the winding key 46, and the closed chamber containing the clock work control mechanism is preferably filled with a light mobile oil—such as kerosene—through a suitable opening such as 59. The head of the winding key and the screw closure of the opening 59 are covered by a suitable packing washer 60 that is held in place by the insertion of the drill stem 11. When the tool is being lowered into the well the drill head members 4—6^a—12^a etc. are suspended on the piston ring 16^{aa}; and the frictional engagement between the flange of this ring and the adjacent flat surface of the threaded nut-gear 37—39 prevents any rotation of the latter by the spring 47. But when the cutters come into contact with the bottom of the bore hole, the weight of the plunger-drill-stem members, 8^a—11 etc., is brought to bear on the mass of lubricant below the piston ring 16^{aa}, and acts to force the viscous material through the restricted duct 120 125 130 135 140 145 150 155 160 165 170 175 180 185 190 195 200 205 210 215 220 225 230 235 240 245 250 255 260 265 270 - 23 to the various bearings of the drill head. This action relieves the frictional engagement between the ring 16^{aa} and the nut-gear 37—39 and leaves the latter free to revolve 5 at a predetermined rate under the influence and control of the clock train, which is set in motion by the angular vibration of the revolving drill members. The speed of descent of the plunger members—relative to 10 the drill head and driving sleeve 6^a—is thus governed by the spring actuated balance wheel mechanism in the plunger head; and the flow of lubricant to the cutter bearings, under the pressure of the drill stem assembly, is thereby regulated and controlled—but not produced—by the aforesaid mechanism. If the flow of lubricant is so slow that the nut is lowered at a more rapid rate than the plunger head the clock movement will 20 be stopped as soon as the face of the gear 39 has been run down into contact with the ring 16^{aa}, and the movement will not be resumed until the subsequent discharge of the lubricating material has again relieved this frictional engagement between the parts.
- In order to provide for the convenient return of the reciprocating members to the starting position (shown in Fig. 4) the 25 threaded tube 12^a is provided, at its upper end, with a squared head; and when the tool has been lifted out of the well, and the drill stem removed therefrom, the tube 12^a can be rotated, by means of a suitable wrench or crank, and the nut 37 can be drawn back to 30 the top of the screw on which it works. In order to provide for this rotary movement the screw sleeve 36 is so set that there is a small endwise clearance between it and the tapered collar 35; and when the latter is 35 lifted from its seat the tube 12^a can be easily turned. But when the drill is in operation the downward thrust of the plunger on the nut 37, and the conjoint pressure of the lubricant on the top of the collar 35 forces the latter tightly against its coned seat and not only prevents any rotation of the tube, but also hermetically seals the opening in which it is supported against any passage of fluid either into or out of the lubricant chamber.
- If the tube is used to carry flushing water from the drill stem 11 to the drill head passage way 33, any access of such water to the bottom of the lubricant chamber is thus 45 effectually prevented.
- The third illustrative embodiment of my present invention—which is shown in Figs. 6 to 9 inclusive—differs from these previously described in having a control mechanism which is actuated by the rotary movement of some part of the drill head and which, therefore, is only in action when the drill is being revolved. In the particular construction here shown the drill head 4 is 50 provided with a driving sleeve 6^b which is substantially identical in form with that
- illustrated in Fig. 4; and the drill stem 11 is attached to a solid plunger member 8^b which slides longitudinally in the said driving sleeve, and is held in nonrotatable relation thereto by means of the keys or lugs 21^b that project from the peripheral edge of the plunger head 16^b and engage with the keyways 20^b. The plunger and plunger head 8^b—16^b are centrally bored to receive a long sleeve 9^b which is normally held in fixed position in these ports by means of a cap nut 32^b. The sleeve is threaded, at its lower end, to receive the control screw 12^b which is rotatably supported in, and on, the cap 61 and the block 62, that rest on the upper face of the drill head 4 and are clamped thereto by the driving sleeve 6^b. The screw is provided with a worm wheel 39^b which is engaged by a worm 40^b that is mounted on the cap 61; and a train of gears 50^b—51^b—52^b—53^b—54^b—55^b and 56^b connect the said worm with an annular gear 57^b that is rotatably mounted between the upper shouldered end of the drill head 4 and the adjacent face of the block 62. The annular gear 57^b is engaged by a pinion 42^b which is mounted on a shaft 41^b that is suitably connected to one of the revolving cutters on the drill head—in such manner, for example, as is indicated in Fig. 10 infra and is more fully illustrated and described in my copending application, Ser. No. 451,223, filed March 10th, 1921. When the drill head rotates and the cutters revolve the screw 12^b is slowly rotated in such direction as to permit the plunger 8^b to descend—under the weight of the attached drill stem parts—and force the lubricant, which is below it, through the ducts 23^b and 23^{bb} to the cutter bearings. If the operation of the drill is stopped the feed of the lubricant is automatically arrested; and if the head of the drill is lifted away from the bottom of the bore hole the separation of the parts—which would result in the expansion of the lubricant reservoir and the sucking in of fluid through the ducts 23^{bb} etc.—is prevented by the engagement of the worm wheel 39^b with the lower face of the bearing in the collar 61. But when it is necessary to refill the reservoir the screw connected members, 4—6^b—61—62 and 8^b—9^b—16^b etc., can be easily returned to their expanded positions by removing the drill stem 11 and the cap nut 32^b and turning the threaded sleeve 9^b by means of a suitable wrench or crank applied to its upper squared end. The lubricant chamber can then be charged through the opening 24^b that is provided for that purpose. The chamber containing the gears 39^b to 55^b is preferably filled with a light mobile oil which can be introduced therein through the screw closed opening 59^b.
- In order to provide for conducting a stream of flushing liquid from the interior of the hollow drill stem 11 to the lower end of

the drill head, the above described construction may be provided with a tube 63 which is screwed into the block 62—and is in communication through a diagonal passageway 5 therein with the opening 33—and which is slidably engaged, at its upper end, with a bearing 19^b at the bottom of the offset opening 64 that extends through the plunger 8^b.

Fig. 9 illustrates a modification of a portion 10 of the structure shown in Figs. 6 and 7. In this modification the screw 12^b is engaged by a split cone nut 65 that is attached to, or forms an integral part of, the split sleeve 9^{bb}; and the latter is secured, at its upper end, 15 to a collar 66 that is, in turn engaged by the clamp nut 32^{bb}. A coil compression spring 67 is interposed between the collar 66 and a shoulder 68 on the plunger 8^b; and serves to keep the sleeve nut 65 pressed upwardly 20 against its coned seat in the plunger head 16^b. When it is desired to separate the members, 11^b and 12^b, the clamp nut 32^{bb} is removed and the sleeve 9^{bb} is pressed down against the tension of the spring 67 thereby releasing the 25 nut sections 65 from their seat, and permitting them to spring apart under the action of the initially tensioned sides of the split sleeve 9^{bb}. The threads of the nut are thus disengaged from the supporting screw 12^b, and the longitudinally slid able driving sleeve and 30 plunger parts may be drawn apart to the original position shown in Fig. 6.

Figs. 10 and 11 illustrate another arrangement of parts in which the flow of lubricant 35 is regulated or governed, but is not produced, by the rotary movement of one of the revolving drill bits. In this construction the rotating cutter member 70—which is of the hyper-conoidic form more fully described in 40 my copending application Ser. No. 442,333 filed Feb. 3rd, 1921—is provided at one end with a ring of gear teeth 71 that engage with a pinion 72 on the end of the shaft 41^c; and the upper end of this shaft carries a skew gear 45 42^c that meshes with an internal gear 39^c on the periphery of the annular drum 73. This drum is fitted rather tightly in a suitable recess in the top of the drill head 4 and is held in place therein by the shouldered end of the 50 driving stem 6^c which is screwed into the threaded extremity of the recessed drill head. The driving stem is secured, at its upper end, to a head 14^c that is provided on its edge with one or more projecting ribs or keys 21^c which 55 are adapted to engage with longitudinal keyways 20^c in the annular plunger 8^c. The driving stem 6^c is longitudinally cored or bored to form a central passage way 64^c, which communicates, at its lower end, with 60 the opening 33 in the member 4, and which is provided, at its upper end, with a bearing 19^c, that engages the tube 63^c. The head 14^c is also centrally bored to receive a split 65 cone sleeve 74 that embraces the tube 63^c and is normally held in frictional engagement

with its seat by the coil compression spring 75. The upper ends of the sleeve 8^c and the tube 63^c are both attached to the cap 9^c which serves to secure these members to the lower extremity of the hollow drill stem 11. The 70 closed annular space between the plunger 8^c and the tube 63^c constitutes the lubricant reservoir; and this is in communication, through the recess containing the split sleeve 74 and the spring 75, with a longitudinal passage 75 way 76 that leads to a peripheral groove 77 on the threaded end of the driving sleeve 6^c. The groove 77 communicates in turn with a duct 78 that is controlled by a needle valve 26^c in the drill head 4; and the lower end 80 of this duct opens into a pocket 79 on the bearing face of the recess in which the drum 73 rotates. The annular web of the drum 73 is pierced with one or more ports 80 which permit of an intermittent flow of liquid from 85 the passage ways 76—77—78 and the opening 79, to the interior of the said drum as the latter is slowly rotated. The lubricant thus admitted to the drum recess is conducted to the bearings of the revolving cutters 70—70' 90 through the clearance space around the split shaft 41^c and the restricted duct 23^c. In order to convert the intermittent flow through the port, or ports, 80, into an equalized or substantially steady flow to the cutter bearings, 95 the lower end of the driving stem 6^c is provided with an air chamber 81 that opens into the drum recess; and when liquid is forced through the ports 80 (by the pressure of the 100 drill stem parts 11—9^c—8^c) it compresses the air that is trapped in this chamber—above the liquid level L—and thus creates an elastic pressure that maintains the flow through the smaller openings, 23^c etc., until the next gush of liquid is admitted to the drum recess. In 105 this case the rapidity of the downward movement of the plunger member—and the consequent speed of discharge of the unguent from the lubricator reservoir—is governed and regulated, in part by the adjustment of the 110 needle valve 26^c, in part by the size and number of the ports 80, in part by the speed of rotation of the drum 73, and in part by the tension of the suspension cable on which the 115 drill stem is hung; and by the preliminary fixed adjustment of the first two factors, or by the controllable surface adjustment of the last two factors, the desired rate of oil supply to the cutter bearings can be maintained at any depth of drilling operations and under 120 any pressure of flushing liquid—if the latter is used.

In the downward movement of the plunger member, relative to the driving sleeve and drill head parts, the split sleeve 74 is disengaged from its coned seat by the sliding friction between it and the tube 63^c. But when the plunger member is raised the sleeve 125 grips the tube and prevents the relative separation of the parts 6^c and 8^c; thus prevent- 130

ing the back flow of liquid into the partially emptied lubricator reservoir in case the port 80 was, at that time, in registry with the opening 79. When the assembly is lifted out of the bore hole and the drill stem is removed, the parts may be easily restored to their original expanded position by taking out the plug 25^a and pressing down the sleeve 74 by means of a suitable tool or implement introduced through this opening in the cap 9^c. The entire structure can be disassembled by removing the cap 9^c from the plunger member, and unscrewing the stem 6^c from the drill head.

The construction shown in Figs. 12 and 13 exemplifies another means for controlling the oil delivery action of a reciprocable plunger member by means of an automatic cutter-operated-valve-mechanism in the discharge circuit. In this construction the drill head 4 is attached to an annular driving sleeve 6^a which is slidably but nonrotatably coupled to a suitable drill stem-plunger member in the manner already fully illustrated in Figs. 4, 5, 6 and 7. The drill head 4 is also provided with a central tube 12^a, which is in registry, at its lower end, with the opening 33 in the said head, and which is slidably engaged, at its upper end with the drill stem plunger in the manner shown in Figs. 1, 3 or 6 (or 14). The upper end of the drill head is cut away to form a T shaped annular recess 82 around the lower portion of the tube 12^a, and the top of this recess is covered by a flange collar 83 that is engaged by the threaded end 35 of the said tube and is also clamped in place by the shouldered extremity of the driving sleeve 6^a. This collar is pierced by a small passage way 76^a that opens into an annular groove 77^a on its lower face; and this groove is in registry with a duct 78^a that communicates at its lower end with the recess 82 in the head 4. The head is also provided with a transverse opening 84 which traverses the duct 78^a, and which contains a reciprocable valve element 73^a; and this valve has on its periphery a circumferential passage or port 80^a, which is adapted to establish communication between the two ends of the duct 78^a, but which is normally held out of registry therewith by means of the spring 85.

The valve member 73^a is actuated by the rotary movement of one of the drill head cutters so as to intermittently open and close the duct 78^a and thereby establish or interrupt communication between the space within the driving sleeve 6^a (which forms the lubricant chamber) and the recess 82. In the particular illustrative construction here shown the tool is provided with reaming cutters 86 which are mounted on short shafts 87, and one of these shafts has a cam groove 88 that engages directly with the outer end of the reciprocable element 73^a. When the higher 65 part of this groove comes in contact with the

stem of the valve the latter is pushed in, against the tension of the spring 85, and a jet of lubricant is forced through the opened duct 78^a into the recess 82 thereby partially filling said recess to a level L, and compressing the air trapped in the upper part of this recess. When the duct is closed, by the spring return of the member 73^a, the trapped fluid will continue to flow through the ducts 23^a, 23da etc., which lead to the cutter bearings, under the action of this compressed air, until the valve is again opened and another supply of lubricant is forced into the drill head chamber.

In the construction shown in Figs. 14 and 15 the gravity action of the drill stem plunger members, in feeding lubricant to the drill head bearings, is governed and controlled by the pressure of the medium—air, gas, or water—in which the boring tool is operating. In this embodiment of my invention the upper end of the drill head 4 is bored out to receive a cylindrical block 62^a that is attached to the said head by a threaded nipple or boss 90 and is also locked in place therein by the shouldered end of the driving sleeve 6^a. This block is longitudinally divided into major and minor sectors that are rigidly connected by eight uniformly distributed screws 91, 91 etc.; and the meeting faces of the two sectors are reversely recessed to form circular chambers 92 and 93 which are separated from each other by the corrugated diaphragm 94 that is inserted and clamped between the connected parts. The center of this diaphragm is engaged by the end of a reciprocable valve element 73^a which is mounted transversely in the minor sector of the block 62^a, and is normally held in open position—as shown in Fig. 14—by a volute spring 85^a, interposed between the diaphragm 94 and the major sector of the said block. This valve element is provided with a U shaped port 80^a; and in the open position last indicated the ends of this port are in registry with the duct 78^a and the opening under the conical head of the valve, thus establishing communication between the lubricant reservoir above the block 62^a and the annular chamber 82^a between the said block and the adjacent wall of the recess in which it is seated. The last named chamber is in communication with the cutter bearings of the drill head through the restricted ducts, 23^a, 23da etc.; and also communicates, through the passage way 95, with the diaphragm chamber 93. The diaphragm-valve block 62^a has a central opening which is in sealed registry, at its lower end, with the passage way 33 in the drill head, and which is threaded at its upper end to receive the tube 63^a; and this opening communicates, through the port 96, with the diaphragm chamber 92.

The driving sleeve 6^a is provided with

three longitudinal keyways, 20°, 20° etc., and is slidably engaged by a tubular plunger member 8° that is attached to the lower end of the drill stem 11 by means of the perforated cap coupling 9°. The hollow plunger 8° is internally beveled and threaded, at its lower end, to receive the head 16° which is also connected to the cap coupling 9° by means of the guard tube 9° and the lock nut 32°. The beveled lower end portion of the member 8° is cut away at three points to receive taper keys 21° that project out into the driving sleeve grooves 20° and hold the relatively reciprocable members 6° and 8° in non-rotatable relation to each other. The plunger head 16° is also provided with a bearing 19° which engages the central tube 63°, and with a port 97 that is normally closed by the spring actuated ball valve 98; and a light piston 99 is fitted to slide longitudinally in the annular chamber between the concentric members 6° and 9°.

In using this last described construction the assembly, of drill head, driving sleeve, and plunger parts, is first inverted—in order to keep the tapered keys 21° out of frictional engagement with the beveled edge of the head 16°—and the relatively reciprocable members are drawn apart to the position shown in Figs. 1, 4, 6 or 10. The piston 99 is also drawn out to the end of the plunger 8° by means of a hook, or other suitable instrument, introduced through one of the openings in the perforated cap 9°—the nut 32° and the perforated screen washer beneath it being removed for that purpose. Both the lower annular reservoir (between the drill head block 62° and the plunger head 16°) and the upper plunger chamber—between the head 16° and the piston 99—are then filled with lubricant through a suitable opening in the piston (e. g., the one normally closed by the screw plug 25°); and when the parts are again brought to their upright position a part of this lubricant will flow by gravity through the passages 78° and 80° and partially fill the drill head chamber 82° thus trapping a considerable volume of air in the upper end thereof. When the charged assembly is lowered to operating position the drill head and driving sleeve parts are supported by the contact of the cutter members with the bottom of the bore hole and the weight of the plunger-drill-stem members is then brought to bear on the mass of lubricant below the head 16°. The valve 98 prevents any back flow of this material into the upper chamber and the pressure on the confined mass forces it, through the still open valve 73°, into the chamber 82° more rapidly than it can be fed therefrom to the cutter bearings. The increased pressure thus produced in the drill head chamber—which is transmitted to the diaphragm chamber 93 through the pas-

sage way 95—soon exceeds that of the fluid surrounding the drill head and filling the passages and chambers 33—96—92 etc.; and the diaphragm valve, 94—73°, is then closed—as shown in Fig. 15—against the preadjusted tension of the spring 85°. The accumulated lubricant in the chamber 82° will continue to flow through the restricted ducts, 23, 23° etc., under the action of the compressed air that was trapped in the upper part of that chamber, until the pressures on the two sides of the diaphragm 94 are nearly equalized; and when this occurs the valve 73° will be again opened by the spring 85° and a fresh charge of unguent will be forced into the drill head chamber by the gravity pressure of the drill stem parts on the material in the main lubricant reservoir.

When the tool is raised out of contact with the bottom of the hole the weight of the parts, 4—6°, etc., will tend to expand the partially contracted reservoir between the heads 16° and 62°, and permit of a back flow of fluid into the lower end of this chamber. In the construction now being described, any such backflow is prevented or modified by three cooperating actions, viz.; (1) the closure of the valve 73° by the effect of any reverse movement of liquid past its coned head and into the outer end of the U shaped port 80°; (2) the frictional locking of the wedge shaped keys 21° between the relatively inclined surfaces of the driving sleeve 6° and the plunger head 16°—which tends to prevent any longitudinal separation of these parts—and (3) the opening of the valve 98—which will immediately follow any separation that does take place by reason of the slipping of the friction lock last mentioned—which will permit of an additional supply of lubricant being forced into the main reservoir by the pressure of the external fluid on the piston 99. This organization, indeed, permits of the continual replenishment of the material in the lower chamber until the charge in the upper chamber has been completely exhausted; and thus reduces the necessary range of reciprocable movement of the parts 4 and 11 without decreasing the possible length of run of the tool. But this last feature of construction is more fully set forth in a copending application, Ser. No. 582,860 filed Aug. 19, 1922, and is not herein claimed.

All of the devices hereinbefore described are in no way dependent in their action on the presence or absence of a column or current of flushing liquid in the bore hole. Any one of them will act effectively in automatically maintaining a forced flow of lubricant to the drill head cutter bearings when the tool is operating in either a dry hole or in water. But one of the major features of my invention—viz., the utilization of the weight of the drill stem to effect the forced feed of lubricant to the cutter bearings—can be embodied

in various constructions in which the flow of flushing liquid through the drill stem, or around the drill head, is utilized to govern and control the rate of feed of the oil or 5 other unguent under the effect of the said weight. One illustrative example of such a construction is presented in Fig. 16. In this exemplification of my improvements the lubricant is contained in the annular chamber 10 between the driving sleeve 6^f and the central tube 63^f through which the flushing liquid is conducted to the opening 33 in the drill head 4;—the arrangement of these parts with respect to the drill stem-plunger assembly 15 being substantially the same as shown, for example, in Fig. 14. The upper end of the drill head passage way 33 is enlarged to form an offset recess in which a turbine wheel 100 is revolvably supported by a vertical shaft 20 41^f that passes upward through the block 62^f and carries at its upper end a pinion 42^f. This pinion engages an internal gear 39^f on the inner periphery of the drum 73^f which is rotatably mounted in a chamber between the 25 block 62^f and the cap 61^f. This cap and block are held together by the threaded end of the tube 63^f, and are also clamped, as a unit, against the upper face of the drill head 4 by the shouldered end of the driving sleeve 6^f. 30 The cap 61^f is provided with a passage-way 78^f; and the drum 73^f has a U shaped port 80^f which is adapted to be brought into registry with the lower end of the said passage-way as the drum rotates, and thus establish a momentary communication between the lubricant reservoir and the chamber containing the revolving drum. When this communication is opened 35 the space between the members 61^f and 62^f is partially filled with lubricant by the pressure 40 of the drill stem parts on the material in the main reservoir, thereby compressing the air that is trapped in the upper part of this space; and as the drum 73^f continues to revolve a series of ports 80^f, in its periphery, 45 are brought successively into registry with the opening 79^f in the edge of the block 62^f, thereby permitting the oil in the said space to pass therefrom to the distribution groove 82^f on the edge of the drill head 4, from whence it 50 passes in turn, through the restricted ducts, 23^f, 23^f etc., to the cutter bearings. In this construction the rate of rotation of the revolving valve member 73^f—and the resultant discharge of lubricant through the intermittently 55 opened passage ways 78^f—is determined in part by the velocity of flow of flushing liquid through the conduit 63^f and over the vanes of the turbine wheel 100; and this velocity of discharge may therefore be controlled from the surface of the ground by varying the rate of supply of water to the hollow drill stem, as well as by varying the tension of the supporting cable therefor.

The turbine element, or some other suitable rotor, may, of course, be used to actu-

ate the control mechanisms that are shown in Figs. 4—5—6—7—10—12 and 13; or conversely any of the actuating devices there shown,—e. g., a gravity or a spring operated clock element, a revolving cutter drive, or some other equivalent instrumentality—may be used to rotate the control valve member of the last described organization. And it will now be apparent to engineers and others familiar with various species of deep well apparatus (such as rotary drills, reamers, pumps, etc.) that the several exemplifications of my invention hereinbefore presented may be modified in many other respects—for the purpose of best adapting my improvements to different types and forms of such apparatus—without essentially altering the characteristic features thereof. The herein described embodiments of the present invention are, therefore, to be regarded as only illustrative of many possible developments and utilizations of my improved lubricating system; and are not to be considered as suggesting or imposing limitations on the field of such developments.

I claim:

1. In a mechanism for feeding lubricant to the bearings of deep well drills the combination of a reservoir in the drill head, a plunger member attached to the drill stem and adapted to move downward with respect to said drill head and reservoir, and means for automatically controlling the rate of relative vertical movement of the said parts for the purposes specified.
2. In a lubricating device for deep well drills the combination of a drill head containing a lubricant chamber, a plunger member longitudinally reciprocable with respect thereto, a drill stem attached to said plunger member, and means for supporting a portion of the weight of said drill stem and plunger on the said drill head.
3. A lubricating device for deep well drills which comprises a drill head for supporting the cutter bits, a lubricant chamber communicating with the cutter bearings, a plunger member adapted to move longitudinally with respect to the said drill head and chamber and thereby vary the volumetric capacity of the latter, a drill stem attached to said plunger, and a control mechanism responsive in operation to an extraneous force for transmitting a predetermined part of the weight of the said drill stem to the drill head and thereby maintaining the cutter bits in proper pressure engagement with the bottom of the bore hole.
4. In a rotary boring tool the combination of a drill head, a driving sleeve connected thereto, a plunger member adapted to move longitudinally with respect to said sleeve, means for holding said plunger and said sleeve in nonrotatable relation, a drill stem attached to said plunger, and an externally

adjustable means for transmitting a portion of the weight of said drill stem to the drill head and thereby maintaining the drill head cutters in predetermined pressure engagement with the bottom of the bore hole.

5. In a lubricating device for deep well rotary drills the combination of a drill head for supporting cutter bits, a drill stem for imparting rotary movement thereto, a pair of relatively slidable members interposed between said head and said stem and forming in conjunction therewith a lubricant chamber of variable volume, means for automatically governing the rate of closing movement of said sliding members whereby the discharge of lubricant from the said chamber is controlled, and other means for holding said relatively slidable parts in fixed relation when the drilling operations are arrested.

10. A mechanism for supplying lubricant to deep well apparatus which comprises a lubricant reservoir having a lubricant delivery duct communicating therewith, a plunger member reciprocating therein and acting 20 on the lubricant contained therein, a confined liquid opposing the movement of said plunger on the suction side thereof, and regulable means for controlling the movement of said plunger by regulating the rate of release 25 of said confined liquid.

6. A lubricating device for deep well drilling apparatus or the like, including two relatively movable members forming a lubricant chamber of variable volume and having a 30 lubricant delivery duct, means for imposing a lubricant feeding force on one of said members for discharging lubricant through said duct and suction means responsive to such force and independent of the resistance of the 35 flow of the lubricant for controlling the movement of said member in feeding lubricant, and means for adjusting the delivery area of said duct.

7. The combination in deep well drilling 40 apparatus or the like, a head member, a sleeve secured thereto for receiving lubricant, a plunger operating within said sleeve to force lubricant therefrom, a stem member secured to said plunger for imparting lubricant delivering force thereto, a second plunger having a liquid delivery duct formed therethrough, means associated with said stem member and said second plunger for confining liquid in said stem member and means 45 for rigidly securing said second plunger to said head member.

8. A lubricating device for deep well drilling apparatus having a lubricant chamber of variable volume formed by complementary sleeves and having a lubricant delivery duct communicating therewith, means for imposing a lubricant feeding force on one of said members to discharge lubricant through said duct and means rendered effective by the application of said force for con-

trolling the relative movement of said members by partially opposing said lubricant feeding force.

10. A lubricating device for deep well drilling apparatus having a lubricant chamber of variable volume formed by complementary sleeves and having a lubricant delivery duct communicating therewith, means for imposing a lubricant feeding force on one of said members to discharge lubricant through said duct, and means rendered effective by the application of said force and independent of the resistance to the lubricant flow for controlling the relative movement of said members by partially opposing said lubricant feeding force.

11. In a lubricant feeding device for deep well drills the combination of a drill head, a lubricant chamber, a plunger member longitudinally reciprocable with respect to said chamber, a drill stem attached to said plunger member, the weight of said drill stem and plunger being supported on said drill head, and a suction operated means for controlling the effectiveness of the force of said weight.

12. In a rotary boring tool the combination of a pair of complementary members forming a lubricating chamber for the cutting tools thereof, means for impressing the weight of the drill head upon said complementary sleeves for compressing the lubricant therein, and suction operated means for opposing said compressive force.

13. A lubricating device for deep well drills which includes a drill head for supporting the cutter bits, a driving sleeve secured to said drill head, a plunger sleeve complementary with said driving sleeve and mounted therein for longitudinal movement with respect thereto, a piston mounted on said drill head and positioned in said plunger sleeve, so that the lubricant feeding force produced by the compressive weight of said tool will be opposed by a suction force between said piston and said plunger.

14. A lubricating device for deep well apparatus which includes two simultaneously rotatable and relatively slidable members forming a lubricant chamber of variable volume, means locking said members against relative rotation with respect to each other, regulable means for restraining the rate of closing movement of said slidable members without varying the rate of their rotation whereby the rate of discharge of lubricant from said chamber is restricted, and other means withholding the separation of said members and limiting the expansion of said chamber.

15. A lubricating device for deep well drilling apparatus or the like comprising a sleeve secured to a drill head member, a plunger operating within said sleeve, a stem member secured to said plunger for imparting lubricant feeding force to said plunger, a

piston spaced from said drill head member in immovable relation thereto and operating within said plunger member, a valve controlled duct in said piston and regulable means for varying the effective area of said duct.

In testimony whereof I have hereunto set my hand.

FRANK L. O. WADSWORTH.
